INMAN TUCKER, OF YUBA CITY, CALIFORNIA.

MACHINE FOR CLEANING RAISINS.

1,170,026.

Specification of Letters Patent. Patented Feb. 1, 1916.

Application filed March 30, 1915. Serial No. 18,017.

To all whom it may concern:

Be it known that I, INMAN TUCKER, a citizen of the United States, residing at Yuba City, in the county of Sutter and State of California, have invented certain new and useful Improvements in Machines for Cleaning Raisins, of which the following is a specification.

My invention relates to a machine for cleaning raisins and the like.

The primary object contemplated by the invention is to provide a machine in which the pneumatic principle is employed to separate the stems and foreign matter from the raisins.

A further object of the invention is the provision of agitating means in combination with the pneumatic principle for the purpose of insuring a maximum cleansing of the raisins.

A still further object of the invention is to provide a cradle which may be adjusted with facility to control the volume of raisins subjected to the cleansing process.

Still another object is to combine with the agitating device and pneumatic principle, raisin combing means for the purpose of freeing the raisins of any stems and the like which might adhere after the pack has been subjected to initial agitation.

To the accomplishment of the recited objects and others coördinate therewith, the preferred embodiment of my invention resides in that construction and arrangement of parts hereinafter described, illustrated in the accompanying drawings, and embraced within the scope of the appended claims.

In said drawings:—Figure 1 is an elevation of the complete machine partly shown in section. Fig. 2 is a top plan view of a portion of the cradle. Fig. 3 is a side elevation of the stem picker, and Fig. 4 is a fragmentary top plan view thereof.

The invention comprises a hopper leading from a source of supply, a conveyer, a supply chute, a discharge chute, an intermediate perforated cradle, a blower, and means for agitating the chutes and cradle. In practice, the raisins are fed from the hopper to the conveyer, then onto the supply chute from which they gravitate to the cradle. This cradle is arranged in close proximity to the outlet end of a blower and is preferably secured to the lower edge of said supply chute, while both chutes and the cradle are mounted in such manner that they may be

agitated in a horizontal plane. It is also essential that the cradle be disposed in the path of the air draft and properly located with respect to the discharge chute whereby the air issuing from the blower outlet will be simultaneously deflected against opposite extremities of the cradle with the result that the air passes through the perforations of the cradle, strikes the mass of raisins while being agitated and blows the stems, foreign matter, etc., over the edge of the chute; leaving the cleansed raisins to fall onto the discharge chute. As a matter of fact the supply and discharge chutes present an inclosure in which the cradle is disposed to receive to best advantage the currents of air issuing from the blower. In combination with the foregoing described arrangement, as a means for positively insuring the separation of the large stems, grapevines, boxboards, etc., from the raisin pack, I employ a combined reciprocatory and semi-rotary picker which combs the raisins and lifts said foreign matter to a point in the path of the forced air current where they are suddenly tripped and simultaneously blown over the butting board of the cradle.

Referring more particularly to the drawing the numeral 1 designates a hopper which is in communication with a suitable supply of raisins, and 2 an endless conveyer mounted upon the frame-work 3, the upper end of said conveyer being disposed in close proximity to one end of a supply chute 4. Hingedly connected at 5 to the bottom of this chute is a cradle 6 having perforations 7 and having a relatively short curved forward end wall 8 merging into a relatively long curved bottom 9. In actual practice it has been found that perforations having dimensions of $29/32''$ give the best results. At the rear end of the cradle there is mounted the vertically extending lug 10 and this lug carries a thumb screw 11 which is designed to enter the openings 12 formed in the vertical side of the chute 4 for the obvious purpose of raising or lowering the cradle. The rear end of the cradle is secured to a butting board 13 provided at its upper end with a forwardly projecting lip or baffle 13^a which serves to prevent the raisins from being forced over the front edge. The determination of the curvature of the bottom of the cradle is a feature of the greatest importance in this machine, the configuration finally adopted being the re-

sult of experiments extending over a considerable period of time. Tests with cradles having dished perforated bottoms, the ends of which occupy the same plane have been 5 found to be ineffective in securing the desired results for the reason that the raisins have a tendency to work toward the rear end of the cradle and are thus prevented from being subjected to repeated agitations 10 which is essential in carrying out the method in a thoroughly satisfactory manner. Flat horizontally disposed cradles are practically useless, as are also inclined flat cradles, as 15 the mechanism employed for agitating the raisins to effect separation therefrom of the stems and any foreign matter cannot coact with the cradle in a manner that will secure the result desired. After repeated trials 20 it has been found that if the bottom of the cradle be disposed on an incline with its forward end lower than its rear end, and with its forward end wall formed on a relatively short curve and its bottom on a relatively long curve, that in the operation of 25 the machine the raisins will be caused always to work toward the forward end of the cradle, thus to permit the product to be subjected to the most advantageous action of the elements employed in effecting its cleansing. This is due to the fact that both the 30 blast and agitating mechanisms are disposed at the front end of the cradle, and as the greatest bulk of the product will, as above stated, be disposed at the front end of the cradle; it follows that a more rapid and effective cleansing can be secured, owing to the attrition resulting from the comparatively large bulk of the product, than would result if the product were in a relatively 35 thin sheet that would be constantly moved away from the cleansing elements. Immediately adjacent the wall 8 of the cradle is the outlet end 14 of a fan blower 15, the same being preferably beveled so as to deflect 40 the air directly against the front of the cradle and also against the rear wall of the discharge chute 16, as indicated by the arrows 17. The supply chute cradle and discharge chute are preferably suspended 45 from the frame 3 by means of the links or hangers 18 and the several parts considered as an entirety are adapted to be agitated in a horizontal plane by means of the eccentric shaped shaker arm 19 which is pivotally 50 connected to the bottom of the discharge chute 16. It will also appear obvious that the supply and discharge chutes virtually 55 comprise an inclosure in which the said cradle is properly disposed to receive the air currents coming from the blower. 60

Coöoperating with the hereinbefore described cradle, air draft, and agitating means, there is employed certain mechanism designed to positively separate such stems, foreign matter and the like as may

still adhere to the raisins after the pack has been subjected to the preliminary treatment. As best shown in Figs. 3 and 4, this mechanism comprises a super-support or platform 70 20 suitably connected to the frame 3 by uprights 21. Rising vertically from the support 20 are a plurality of vertical bearing posts 22, each carrying at its upper extremity a pair of anti-friction rollers 23. Yieldably connected to the support 20 by means of coil springs 24 is a series of arms 25, the upper end of each of which carries a bearing plate 26 adapted for engagement with each pair of adjacent rollers 23, while the lower ends of said arms are fashioned 75 into fingers 27. The intermediate portion of each arm is connected by means of the knuckle 28 to a horizontally disposed crank shaft 29 carrying a pulley 30 on its outer terminal. The arms project downwardly at 80 an inclination and extend through elongated slots 31 in the support 20.

As the raisins together with their stems, foreign matter, etc., are fed into the chute 4, and in turn to the cradle 6 the entire mass 90 is agitated by the shaker arm 19 and simultaneously the forced air draft issuing from the outlet 14 of the blower 15 passes through the perforations in the rear curved portion of the cradle, thereby forcing the raisins 95 toward the center of the cradle. At the same time a portion of the air will pass beneath the cradle 6, strike the rear upper extremity of the discharge chute 16 and from this point will be deflected through 100 the perforations 7 in the opposite end of the cradle, it being remembered that the raisins are being continually agitated and that the opening in the opposite ends of the 105 cradle are alternately uncovered by the raisins to permit the free passage of air therethrough.

Manifestly the purpose of the lip 13 is to prevent the raisins from being blown over the edge of the cradle. If it should be found 110 desirable to control the output of cleansed raisins this may be easily taken care of by an appropriate adjustment of the upper end of the cradle by means of the thumb screw 11. For example by elevating the cradle the 115 mass of raisins is diminished, allowing a more free passage of air and consequently less volume of raisins. By lowering the cradle the mass becomes greater and tends to choke the air supply, thereby allowing 120 the agitation of the mass to increase the volume of raisins passing through the perforations. It will also be pointed out that the lower portion of the discharge chute 16 is extended beyond the plane of the out- 125 let end 14 of the blower so as to form a positive air pocket.

Simultaneously during the operation of the agitating means and the forced air draft, power is applied to the pulley 30 and by 130

reason of the eccentric disposition of the crank shaft 29, the fingers 27 are caused to describe an extended curve as indicated by dotted lines in Fig. 1. During this movement the fingers serve to thoroughly comb the raisins, and separate and lift therefrom such large stems, grapevines, etc., as may be present in the pack. The elevating of the foreign matter occurs at a point adjacent to the rear end of the cradle and simultaneously the fingers have imparted to them a slight "kick" by reason of the disengagement of the plates 26 with the rollers 23—which combined with the air blast forces said foreign matter over the butting board 13.

It should be understood that in its broader aspect the invention comprehends the employment not only of the various means described, but of equivalent means for performing the recited functions.

While the arrangement shown is thought at the present time to be preferable, it is desired to reserve the right to effect such modifications and variations thereof as may come fairly within the scope of the appended claims.

What is claimed, is:—

1. In a machine of the class described, the combination of a supply chute, a discharge chute, a cradle interposed between said chutes and having a relatively short foraminous forward wall, means for forcing an air draft against said wall, and means for agitating said chutes and said cradle.

2. In a machine of the class described, the combination of a supply chute, a discharge chute, a perforated cradle interposed between said chute and having a relatively short curved front wall and a relatively long curved bottom, means for forcing an air draft against said forward wall, and means for agitating said chutes and said perforated cradle, and reciprocatory agitating mechanism working within the cradle.

3. In a machine of the class described, the combination of a perforated cradle, means for supplying raisins to said cradle, means for forcing an air draft against said cradle, means for agitating the cradle, and combing mechanism working within the cradle.

4. In a machine of the class described, the combination of a foraminous cradle,

means for supplying raisins to said cradle, means for forcing an air draft against said cradle, and combing mechanism working within the cradle.

5. In a machine of the class described, the combination with agitating means, of an inclosure having an inlet and outlet, a perforated cradle disposed in said inclosure between said inlet and outlet, and means for directing an air current through the perforations of the front wall of said cradle.

6. In a machine of the class described, the combination with agitating means, of an inclosure having an inlet and outlet, a perforated cradle disposed in said inclosure between said inlet and outlet, reciprocatory agitating mechanism coacting with the cradle, and means for directing an air current through the perforations at opposite ends of said cradle.

7. In a machine of the class described, the combination of a perforated cradle, means for forcing an air draft in proximity to said cradle, a picker arm adapted to comb and elevate the foreign matter combined with the raisins, and means for imparting a kick to said arm in the path of said air draft.

8. In a machine of the class described, the combination of a perforated cradle, means for forcing an air draft in proximity to said cradle, a picker arm adapted to elevate the raisins above said cradle, and means for tripping said arm to cause said raisins to drop in the path of said air draft.

9. In a machine of the class described a reciprocatory foraminous cradle having its front end lower than its rear end, blast mechanism coacting with the front end, and picker mechanism coacting with the cradle.

10. In a machine of the class described, an inclined foraminous cradle having a short curved front wall disposed in a plane below the rear end of the cradle, blast mechanism co-acting with the front wall, and combined reciprocatory and semi-rotary picker mechanism disposed within the cradle.

In testimony whereof I affix my signature in presence of two witnesses.

INMAN TUCKER.
